UNITED STATES PATENT OFFICE

2,503,227

SHOE TREE

Howard C. Vining, Brockton, Mass., assignor to
 Jones & Vining, Inc., Brockton, Mass., a corpora-
 tion of Massachusetts

Application August 5, 1947, Serial No. 766,281

1 Claim. (Cl. 12—128.6)

1

My present invention is a novel and improved shoe tree or display form.

Important objects of the invention are to improve and perfect this type of device and to enable the same to be made quickly, economically, and with the desired degree of adjustment to fit varying sizes of shoes.

Heretofore, it has been customary to make shoe trees usually of a skeleton type to save expense, such trees being ordinarily made with small toe portions and skeleton heel sections with a toggle or hinge connecting the same. While this type of skeleton shoe tree could be made cheaply and economically, it was not satisfactory as failing to give a full, smooth, and firm support to the shoe upper to which the tree or display form was fitted, leaving the upper wrinkled and unsupported, particularly around the top and sides.

Other types of shoe forms which were specially made as a full-sized last involved undue expense and weight, with more or less complex connecting toggles, hinges, or other joint constructions, particularly where a lengthwise adjustability was involved.

My present invention is directed to provide a full supporting shoe tree to keep the entire area of the upper supported, smooth from wrinkles, and particularly to have the cone portion of the display form extending to or above and entirely around the topmost edge of the forepart, as well also as filling the ankle portion of the shoe, thus giving a better and more attractive display feature, together with an extremely economical, quick, and easy lengthwise adjustment, with a single connecting link or member.

A further feature consists in the special curvature of the heel portion of my improved shoe tree or display form which will facilitate the fitting of the shoe tree into a shoe, as well as the removal therefrom, without unduly stretching the shoe upper or distorting the same from its design, style, size, and length.

A special feature is the line of cut between the forepart and heel part which facilitates the pivotal action between the fore and heel parts of my shoe tree and cooperates with the heel portion to permit quick application to or removal from a shoe.

A further and special feature is the relative position of the pivot for the heel cooperating with the curvature of the rear part of the heel which insures an immediate shortening of the last at the initiation of the bending or collapsing movement from lengthened position to collapsed position.

2

Thus the heel part is drawn away from the heel of the shoe and prevents straining the upper.

Referring to the drawings illustrating a preferred embodiment of my present invention:

- 5 Fig. 1 is a side elevational view partly in cross section showing the shoe tree in extended position, and
- 10 Fig. 2 is a corresponding side elevational view showing the shoe tree in collapsed position.
- 15 As shown in the drawings, my improved shoe tree or form comprises the forepart 1 and heel portion 2 to which may be fitted a handle 3. The line of cut dividing the forepart and heel part is of special importance: On the forepart it comprises two lines, one as indicated at 4 extending downwardly below the level of the connecting link; and a second line of cut 5 which is at a slightly different angle to facilitate seating and locking of the two parts when in extended position.
- 20 On the heel portion 2 the line of cut is indicated at 6, which is practically straight and is at a sufficient angle with the lines of cut 4 and 5 on the forepart so as to permit rocking or flexing of the heel part relatively with the forepart on a single pivot point, with the connecting link relatively rigid with the forepart and the heel part—in effect, rocking on the link-connecting pivot. The heel part also is provided with a saw cut or kerf 7, which can be made from the line of cut 6 inwardly substantially in the middle portion of the heel part, the saw cut terminating as indicated at 17, giving a relatively deep kerf so that the connecting pivot will be located well within the solid wood of the heel part.
- 25 The connecting link comprises a middle member 10 having one portion 11 flattened to a thickness substantially equal to the width of the kerf 7 so as to give a lateral bearing therein but with sufficient clearance to permit a rocking action of
- 30 40 the heel part on said flattened link portion 11.
- 35 This link portion 11 is provided with an opening thru which a pivot pin 12 will pass, extending from the outside of the heel part as indicated in Fig. 2, and giving a firm pivotal bearing of the heel part on the link 10. The link 10 has the opposite or forward portion formed round and treated to be threaded into a bored opening 15 in the forepart, the diameter of the threaded portion 14 of the link 10 and that of the bore 15 being such as to permit the threads on the link 10 to cut into and form a correspondingly threaded or tapped contour in the bored opening 15. Thus, with the link 10 threaded into the forepart, and the pivot 12 uniting the opposite end of the link to the rear part, a quick adjustment length-
- 45 50 55

wise is effected by rotating the heel part relatively with the forepart, and the threaded portion of the link being thus shortened or lengthened, thereby giving a lengthwise adjustment of both parts.

The cone portion of the heel part 29 is of sufficient length to act as a support for the tongue and lacing part of the shoe, or of the vamp if a slipper, pump, or the like is to be fitted on this shoe tree or form, while the particular curved portion 21 at the bottom of the heel, as indicated, is on a radius with the pivot 12 to permit and facilitate the fitting in or removal from the shoe of my improved shoe tree.

Preferably the lower portions of the lines of cut between the forepart and heel part may be bevelled slightly, as indicated at 18, on the line of cut 5, and at 16 on the bottom part of the cut 6 on the heel part to prevent pinching the lining.

It will thus be appreciated that my novel and improved shoe tree or display form gives a full and complete support to the shoe upper throughout its entire extent and fills the angle portion of the shoe so that it can be fitted to or removed therefrom without difficulty or straining by reason of the position of the pivot 12 and the heel curve 21, while the forepart and heel part can be quickly adjusted lengthwise, and all with an extremely simple construction and a single link, independently of toggles, catches, locks, or the like.

The bore 15 in the forepart is also at a precise and predetermined angle with relation to the pivot 12 in the heel part and the curved portion 21. The assembling of both parts is accomplished by simply positioning them together and driving in the pivot pin 12, which can be accomplished without skilled labor and with great speed and at a minimum of expense.

My invention of a last form with a single connecting element which keeps the forepart and heel part in correct alignment by the flattened portion 11 in the kerf 7, while permitting ad-

justment by rotating the link on the threads in the forepart, insures accurate alignment of both parts and greatly facilitates the assembling operation.

5 I claim:

A shoe tree, display form, or the like of the kind described, having a substantial forepart with a longitudinally central bored opening angularly positioned with regard to the bottom of the forepart, together with a heel portion having a complete ankle-supporting portion formed with a straight line of cut adjacent the forepart, and a circular relatively narrow saw kerf opening from said line of cut into the heel part, said two parts being pivotally and lengthwise adjustably united by a single connecting link, said link having a threaded part adapted to be threaded directly into the wood of said angular recess in the forepart, and a flattened portion adapted to fit within said saw kerf and being held to the heel part by a single pivotal pin, said link holding said forepart and heel part adjustably spaced sufficiently to permit relative flexing of said parts to allow insertion in and removal from a shoe without straining the upper, and while supporting the ankle portion of the upper.

HOWARD C. Vining.
